PICTURE STORAGE AND DISPLAY CABINET

Edward J. Morin, Omaha, Nebr.

Application August 4, 1936, Serial No. 94,228

1 Claim. (Cl. 312—181)

The invention relates to a cabinet for storing and displaying pictures, valuable papers, and the like, and has for its principal object the provision of a means for the purpose stated that will adequately protect the pictures, etc., while stored, and also providing means whereby the material may be readily displayed and examined.

A further object of the invention is the provision of a device of the class described including a cabinet receptacle having grooved guide means in which are slidably mounted bars or posts carrying pivotally mounted plates or panels having clips or the like to which pictures, valuable papers, and the like may be secured, the bars or posts being slidably mounted relatively to the cabinet receptacle, and the cabinet provided with doors or other closures to protect the contents of the receptacle during storage.

The invention will be described in detail hereinafter and will be found illustrating the accompanying drawing in which:

Figure 1 is a view in perspective of the improved storage and display cabinet;

Figure 2 is a sectional view on a plane indicated by the line 2—2 of Figure 1;

Figure 3 is a horizontal sectional view on a plane indicated by the line 3—3 of Figure 2;

Figure 4 is a vertical sectional view on a plane indicated by the line 4—4 of Figure 2;

Figure 5 is a fragmentary detail of the outer end of the groove guide mounted at the top of the receptacle, and

Figure 6 is a similar view of the groove guide mounted at the bottom of the receptacle.

In the drawing similar reference characters are used to designate corresponding parts in all of the views.

The device comprises a cabinet structure 10 including a receptacle portion 11 having top and bottom walls 12 and 13, respectively.

Secured to the walls 12 and 13, respectively, are channeled guide members 14 and 14^a, respectively, said channeled members having in-turned flanges 15 having their adjacent edges spaced from one another and providing elongated openings 16 admitting to the interior of said guide members. Slidably mounted in said elongated openings 16 are bars or posts 17 having their ends provided with laterally extended portions 18 to prevent removal of the bars or posts through said elongated openings, but permitting sliding movement thereof in said guide members. The outer front ends of the guide members 13 have upwardly extending flanges 19 forming lips, and the guide members 14 are also provided with up-

wardly extending flanges 20 also providing lips, the purpose of said lips 19 and 20 being to limit the outward movement of the bars or posts 17 relatively to the cabinet receptacle, except when said bar or post is lifted over said lips in removing or replacing the members in the groove guide.

Each bar or post 17 is provided with two or more eyeleted pins, or screw eyes 21, and 22 designates plates or panels having angular pins 10 secured in their edges and fitting into the loops of eyeleted pins 21 and thus hingedly mounting said plate or panel to a bar or post.

The plate or panel 22 in each instance is provided with a plurality of clips or other holding means 23 to accommodate pictures, photographs, valuable papers, and the like for storage and display on said plate or panel.

The open front of the receptacle 11 is provided with a suitable closure which is shown in the drawing as hinged doors 24, 25 designating the hinges pivotally securing said doors to the walls 20 of the receptacle. In the base of the receptacle is slidably mounted a drawer 26 that may be utilized for any purpose desired.

It will be understood from the above description and the accompanying drawing that the cabinet may be made a desirable article of furniture suitable for a drawing room, or an office or a mercantile establishment, and may if desired be mounted on legs or be supported on a table or store counter or the like, and that the pictures or other material that may be displayed and secured to the plates or panels 22 may be readily inspected when the doors 24 are opened 35 by pulling the cabinet and its mounting bar or post outwardly of the receptacle through the provision shown in dotted lines in Figure 3 at which time the plates or panels may be examined on opposite sides thereof by turning them from right 40 to left by means of the hinge connections 21—23. The edges of the inturned flanges 15 will prevent the panels or plates interfering with one another in the receptacle, each plate or panel being kept substantially in alignment with the bar or 45 post to which it is secured.

I claim as my invention:

A device of the class described comprising in combination with a cabinet provided with swinging doors, guideways mounted in said cabinet on the top and bottom walls thereof in opposed relationship, said guideways being channel shaped and provided with inturned flanges spaced from each other and forming slots therebetween, supporting members slidably mounted in said 55

guideways in vertical parallel relationship to support display racks, said supporting members having enlarged ends to prevent removal of the members through said slots, said supporting members 5 being of a length to permit the lower enlarged portions to engage the bases of the lower guideways and the upper enlarged portions to engage the flanges of the upper guideways, the thickness • of said enlarged portions being substantially less than the height of said guideways to provide a

space between the enlarged portions and the tops of the guideways, and said guideways having upturned end portions at their outer open ends forming spaces between said upturned end portions and the tops of said guideways greater 5 than the thickness of the enlarged portions to permit said supporting members to be lifted and removed from said guideways.

EDWARD J. MORIN.
